UNITED STATES PATENT OFFICE

FRED ASHWORTH, OF BEVERLY, MASSACHUSETTS, ASSIGNOR TO UNITED SHOE MACHINERY CORPORATION, OF PATERSON, NEW JERSEY, A CORPORATION OF NEW JERSEY

SEWING MACHINE SHUTTLE

Original application filed February 9, 1929, Serial No. 338,756. Divided and this application filed May 1, 1930. Serial No. 448,909.

The present invention relates to sewing machine shuttles and has for its object providing a construction and arrangement of parts intended to facilitate the insertion of the shuttle thread into the shuttle and the threading of the shuttle ready for use. Certain features of the invention are also intended to facilitate the use of a thread cop instead of a bobbin and permit the thread to be drawn from the center of the cop if such a mode of operation is desired. In embodying these features of the invention in the illustrated shuttle, an improved removable thread holder or thread case for the shuttle has been provided, which can be completely threaded before being placed in the shuttle and which, when placed in the shuttle, will exert the requisite amount of tension on the shuttle thread. The thread case and shuttle also are provided with simple and efficient means which will securely lock the thread case in the shuttle and which can be readily actuated to unlock the thread case and permit its removal.

The shuttle illustrated in the accompanying drawing, embodying the features of the present invention, is that illustrated in applicant's pending application for shoe sewing machines, filed February 9, 1929, Serial No. 338,756, of which the present application is a division.

Referring to the drawing accompanying this application, Fig. 1 is a front view of the shuttle illustrating somewhat diagrammatically its position with relation to the needle and the work; Fig. 2 is a detail front view of the thread holder casing removed from the shuttle; Fig. 3 is a detail sectional plan view of the shuttle and thread holder casing, a portion of the thread holder casing being shown in section on the line 3 in Fig. 2; Fig. 4 is a sectional plan view of the shuttle and thread holder casing illustrating the position of the shuttle with rela-

tion to the shuttle supporting raceway and the shuttle driver.

The shuttle illustrated in the accompanying drawing, embodying the features of the present invention consists of a discoidal shuttle casing 6, the rear end of which is closed and the forward end of which is open to receive a thread holder. The thread holder, as illustrated, consists of a cylindrical thread casing 8, the rear end of which is open to permit the insertion of a cop of thread while the holder is removed from the shuttle, and the front end of which when the thread case is in position in the shuttle, forms a closure for the open end of the shuttle casing. From the closed end of the thread holder casing a hollow stud 10 projects inwardly so as to form a central support for the inserted thread cop. Within this hollow stud a hollow plunger 12 is arranged which is acted upon by a coiled spring 14, tending to force the plunger against the rear wall of the shuttle casing. The hollow stud 10 and hollow plunger 12 form a central thread passage for the shuttle thread opening on the forward end of the thread holder casing, the shuttle thread leading from the interior of the thread cop between the end of the plunger 12 and the rear wall of the shuttle casing where it is subjected to sufficient pressure to produce the required tension on the thread, and then passing through the thread passage formed by the hollow plunger and stud to the outside of the thread case. The cop of thread is placed in the thread case while the case is removed from the shuttle, and it will be apparent that the thread case can be threaded before being placed in the shuttle and that after the thread case is placed in the shuttle casing no further threading of the shuttle is necessary.

In order to lock the thread case securely in position, while permitting its ready removal, locking devices are provided for in

ter-engaging the thread case and shuttle casing at diametrically opposite sides of the thread casing. As illustrated, the inter-engaging locking devices at one side of the casing 5 comprise a flange 16 projecting radially from the inner end of the thread casing, and a slot formed in the adjacent wall of the shuttle casing to receive the flange. The other inter-engaging locking devices 10 comprise a slide 18 mounted in a guide-way extending diametrically across the outer face of the closed end of the thread case and a groove 20 formed in the inner wall of the shuttle casing to receive the end 15 of the slide. With this construction, when the slide 18 is in engagement with the groove 20, as illustrated in Fig. 4, the thread case is held securely in position, while to permit the ready removal of the thread case, it is 20 merely necessary to move the slide 18 inwardly and then tip the thread case slightly so as to disengage the flange 16 from its cooperating slot. In order to hold the locking slide 18 in locking position, a plunger 25 22 is mounted in the hollow stud 10 and is provided with an outwardly extending end arranged to engage a hole 24 formed at the proper point in the slide 18. This plunger is actuated upon by the coiled spring 14 which 30 actuates the plunger 12 and is hollowed in order to form a continuation of the passage for the shuttle thread. The slide 18 may be conveniently unlocked by inserting a suitably shaped tool in the hole 24, thereby 35 forcing the plunger 22 downwardly so as to disengage the slide 18 and allow it to be moved into unlocking position. A sidewise extension 26 of the hole 24 permits proper 40 threading of the thread case while the thread case is removed from the shuttle casing, and while the locking slide is in unlocking position. The forward end of the thread holder casing is provided with radial extensions 28 and 30, diametrically opposite 45 to each other, forming shoulders which cooperate with inwardly projecting shoulders formed in the shuttle casing to prevent rotation of the thread holder casing relatively to the shuttle casing.

50 The nature and scope of the invention having been indicated, and a shuttle embodying the several features of the invention having been specifically described what is claimed is:

55 1. A shuttle for shoe sewing machines comprising a discoidal shuttle casing having an open end, and a removable thread holder forming a closure for the open end of the shuttle casing provided with a central hollow thread supporting stud projecting inwardly into the shuttle casing and forming a thread passage extending through the stud and opening on the outer side of the thread holder.

60 2. A shuttle for shoe sewing machines

comprising a discoidal shuttle casing having an open end, a removable thread holder forming a closure for the open end of the shuttle casing provided with a central hollow stud projecting inwardly into the shuttle casing and forming a thread passage opening on the outer side of the thread holder, and a hollow spring pressed thread 70 engaging plunger mounted in the stud between which and the inner surface of the 75 shuttle casing the shuttle thread passes.

3. A shuttle for shoe sewing machines comprising a discoidal shuttle casing having an open end, a removable thread holder comprising a cylindrical casing having an end forming a closure for the open end of the shuttle casing, means for removably locking the thread holder to the shuttle casing comprising cooperating inter-engaging devices on the thread holder and shuttle casings, a locking slide mounted in the end of the thread holder casing and arranged to move diametrically across the end of the thread holder casing to engage a groove 80 formed in the shuttle casing diametrically opposite said inter-engaging devices and a locking device, for the locking slide.

4. A shuttle for shoe sewing machines comprising a discoidal shuttle casing having an open end, a removable thread holder comprising a cylindrical casing having an end forming a closure for the open end of the shuttle casing, means for removably locking the thread holder to the shuttle casing comprising cooperating inter-engaging devices 95 at one side of the thread holder casing and a locking slide mounted in the end of the thread holder casing and arranged to engage a groove formed in the shuttle casing diametrically opposite said inter-engaging devices, and a spring pressed plunger arranged to engage a hole in the slide when the 100 slide is in locking position.

5. A shuttle for shoe sewing machines comprising a discoidal shuttle casing having an open end, a removable thread holder comprising a cylindrical casing having an end forming a closure for the open end of the shuttle casing, said thread holder casing being provided with a central hollow stud projecting inwardly into the shuttle casing from the end of the thread holder casing, means for removably locking the thread holder casing to the shuttle casing comprising cooperating inter-engaging devices 110 at one side of the thread holder casing, a locking slide mounted in the end of the thread holder casing and arranged to engage a groove formed in the shuttle casing diametrically opposite said inter-engaging devices, and a hollow spring pressed plunger mounted in said hollow stud arranged to engage a hole in the slide when the 115 slide is in locking position.

6. A shuttle for shoe sewing machines 120

comprising a discoidal shuttle casing having an open end, a removable thread holder comprising a cylindrical casing having an end forming a closure for the open end of the shuttle casing, means for removably locking the thread holder casing to the shuttle casing, and means for preventing rotation of the thread holder casing with relation to the shuttle casing comprising projecting shoulders on the outer periphery of the thread holder casing and cooperating inwardly projecting shoulders on the shuttle casing.

5 In testimony whereof I have signed my name to this specification.

10 FRED ASHWORTH.
